UTILITY TRAILER

David K. Kalawaia, La Mirada, and Anthony J. Rivera,
Fullerton, Calif., assignors to Kalawain Boats, Inc.,
Santa Fe Springs, Calif., a corporation of California

Filed Feb. 28, 1966, Ser. No. 1,208

Term of patent 14 years

(Cl. D14—3)

FIG. 1 is a perspective view of one embodiment of a utility trailer embodying our new design;

FIG. 2 is a top plan view thereof;

FIG. 3 is a side elevational view thereof;

FIG. 4 is a fragmentary sectional view taken along line 4-4 of FIG. 2;

FIG. 5 is a sectional view taken along line 5-5 of FIG. 4;

FIG. 6 is a front view thereof;

FIG. 7 is a rear view thereof; and

FIG. 8 is a side elevational view of another embodiment of a utility trailer embodying our new design.

The embodiment illustrated in FIG. 8 is identical to the embodiment illustrated in FIGS. 1-7 except that the former has a single pair of wheels and the latter has two pairs of wheels, this difference being apparent on inspection of FIGS. 3 and 8.

The dominant features reside in the solid line portions.
We claim:

The ornamental design for a utility trailer, substantially as shown and described.
